US0D1042167S

(12) United States Design Patent (10) Patent No.: US D1,042,167 S
(45) Date of Patent: * Sep. 17, 2024

(54) WATCH

(71) Applicant: RICHEMONT INTERNATIONAL SA, Villars-sur-Glâne (CH)

(72) Inventor: Philip Bolthausen, Geneva (CH)

(73) Assignee: RICHEMONT INTERNATIONAL SA, Villars-sur-Glâne (CH)

() Term: 15 Years

(21) Appl. No.: 29/855,764

(22) Filed: Oct. 6, 2022

Related U.S. Application Data

(62) Division of application No. 35/512,340, filed on Feb. 10, 2021 (U.S. filing date under 35 U.S.C. 384), and having an international filing date of Feb. 10, 2021, now Pat. No. Des. 978,684.
